UNITED STATES PATENT OFFICE.

ALBERT C. LOTTMAN, OF HOUSTON, TEXAS.

TIGHTENING DEVICE FOR SPRING BED-BOTTOMS.

SPECIFICATION forming part of Letters Patent No. 634,531, dated October 10, 1899.

Application filed December 31, 1898. Serial No. 700,788. (No model.)

To all whom it may concern:

Be it known that I, ALBERT C. LOTTMAN, a citizen of the United States of America, residing at Houston, in the county of Harris and State of Texas, have invented certain new and useful Improvements in Tightening Devices for Spring Bed-Bottoms; and I do hereby declare the following to be a full, clear, and exact description of the invention, such as will enable others skilled in the art to which it appertains to make and use the same.

This invention is an improvement in spring bed-bottoms, and relates more especially to certain devices which provide a simple and effective means for tightening or adjusting the bed-bottom and securely holding such adjustment, the particular construction and arrangement of said devices forming a means of adjustment that can be conveniently operated, offers no obstruction, and will not become accidentally disengaged, and, further, possesses the very important advantage of being strong and durable.

With the above ends in view the invention contemplates the production of an adjustable bed-bottom or frame for wire-spring mattresses that can be manufactured at small cost and in which the adjustment may be effected without the employment of any supplemental device or tool.

The following specification enters into a detail description of the construction and operation of my invention, reference being had to the accompanying drawings and to letters thereon, which designate the different parts, and what I consider to be the novel features of construction and desire protection upon are more specifically set forth in the appended claims.

In the drawings forming part hereof, Figure 1 is a plan view of a spring bed-bottom constructed in accordance with my invention. Fig. 2 is a sectional view on the line 2 2 of Fig. 1. Fig. 3 is a sectional view on the line 3 3 of Fig. 1. Fig. 4 is a detail perspective view of the operating-lever and gravity-pawl carried thereby.

Referring more particularly to said drawings, A and A' designate the side pieces or longitudinal rails of the frame of the bed-bottom, which are connected to each other at one end by a flat cross-piece A² and at the

other end by a roller B. The roller is provided at its ends with short spindles C, which turn therein and are held in place by caps or ferrules D, the projecting ends of said spindles being passed through the side rails A A' and secured thereto, as shown. This construction prevents spreading of the side rails of the frame and permits the roller to be turned and thereby take up any slack in the wire fabric E, the said fabric being attached at one end to the cross-piece A² and at its other end to the roller for this purpose.

To provide a simple and convenient means for turning the roller and holding the adjustment of the same, I have devised certain attachments which I shall now proceed to describe. In the first place the metal caps or ferrules at the ends of the roller are each provided with a circumferential series of holes d, with which the pawls of the adjusting devices engage. Engaging the holes in one of the ferrules is a pawl F, consisting of a flat strip or plate of metal pivoted at one end to the inner side of one of the side rails of the frame and provided at its free end with a hook f, which engages said holes. The pawl is brought into engagement with the ferrule or holes therein by means of a helical spring f', attached to an intermediate portion of the pawl and to the lower edge of the rail. Engaging the holes in the ferrule at the other end of the roller is a pawl g, pivoted to the intermediate portion of a lever G, which is fulcrumed on the adjoining spindle C, and for this purpose said lever is provided at its end with a hole through which the spindle passes. This lever is preferably a flat plate, and after an adjustment of the roller has been made will lie flat against the inner side of the rail, abutting against a pin H, which is larger at its outer end and tapers inward, so as to cause the lever to ride upon the inclined surface of the pin, bringing said lever to bear closely against the side rail and preventing accidental disengagement thereof.

When it is desired to tighten or take up slack in the wire fabric E, the lever is moved out of engagement with the pin, and the pawl carried thereby being in engagement with one of the holes in the ferrule the lever is raised until the pawl F engages the next hole of the other ferrule, after which the le-

ver is again brought in contact with the pin H, and the pawl g being in engagement with the roller will assist in preventing backward rotation of the same. It will be noted that 5 the end of the pawl g also engages the pin H, and in the normal position of the parts or adjusting devices will provide against accidental disengagement of the said pawl.

The adjusting devices provide a ready and 10 convenient means of turning the roller and holding the adjustment of the same, and the said devices lying closely against the side rails will be out of the way, so as not to offer any 15 obstruction or catch in the hair mattress and other covering which may be placed upon the wire fabric.

Having thus described my invention, what I claim as new, and desire to secure by Letters Patent, is—

20 1. A bed-bottom frame for wire mattresses, comprising the side rails connected to each other at one end by a cross-piece, a roller journaled in the other end of the side rails, said roller having a circumferential series of holes 25 at each end, a pawl pivoted to the inner side of one of the rails to engage one set of holes in the roller, a lever fulcrumed on the other end of the roller, a pawl pivoted to said lever and provided with a projecting rear end, 30 and a pin projecting from the adjoining side rail to contact with the lever and pawl, substantially as shown and for the purpose set forth.

2. A bed-bottom frame for wire mattresses, comprising the side rails connected to each other at one end by a cross-piece, a roller journaled in the other end of said side rails, the roller having a circumferential series of holes 35 at each end, a pawl engaging one set of holes, a lever fulcrumed on the spindle at the other end of the roller, a pawl pivoted to the lever and provided with a projecting rear end, and a pin limiting the throw of the lever in one direction, the said pin being tapered from its outer end inward, substantially as shown and 40 for the purpose set forth.

3. In combination with a frame for wire-spring mattresses, of a roller, short spindles let into the ends of said roller, metal caps attached to the ends of the roller to hold the 45 spindles in place, said caps each having a circumferential series of holes, a pawl pivoted to the frame to engage one set of holes, a lever fulcrumed on the spindle at the other end of the roller, a pawl pivoted to said lever and 50 adapted to engage the other set of holes, and a pin projecting from the frame to limit the throw of the lever in one direction, substantially as shown and for the purpose set forth.

In testimony whereof I affix my signature 55 in presence of two witnesses.

ALBERT C. LOTTMAN.
